Specification for Design.

Patented Oct. 22, 1912.

Application filed February 28, 1910. Serial No. 546,565. Term of patent 14 years.

To all whom it may concern:

Be it known that I, ARTHUR ATWATER KENT, a citizen of the United States, residing at Philadelphia, in the county of Philadelphia and State of Pennsylvania, have invented a new, original, and ornamental Design for Automobile-Horns, of which the following is a specification, reference being had to the accompanying drawing, forming a part thereof.

The drawings show in Figure 1 a side ele-

vational view and in Fig. 2 an end elevational view of an automobile horn, embodying my new and ornamental design.

I claim:

The ornamental design for an automobile horn, as shown.
